UNITED STATES PATENT OFFICE.

JACOB KRONENBERG, OF NEW YORK, N. Y.

DESIGN FOR A HORSESHOE-PAD.

SPECIFICATION forming part of Design No. 32,346, dated March 13, 1900.

Application filed January 23, 1900. Serial No. 2,546. Term of patent 7 years.

To all whom it may concern:

Be it known that I, JACOB KRONENBERG, a citizen of the United States, and a resident of the city of New York, borough of Brooklyn, in the county of Kings and State of New York, have invented and produced a new and original Design for a Horseshoe-Pad, of which the following is a full, clear, and exact description.

Reference is to be had to the accompanying drawing, forming a part of this specification, in which the figure is a perspective view of a horseshoe-pad, showing my design.

The design consists in the horseshoe-pad made the subject of the accompanying illustration, in which appears a horseshoe-shaped flange A, extending from the side and front edges of the body B, said flange being thickened at the ends A' and merging into shoulders B' of the said body B, which latter is formed with approximately-elliptical side portions C² C², joining a similarly-shaped front portion C³, whose outer edge is, however, more

deeply curved than its inner, and a rear portion C', whose outer edge is concave and whose inner edge is convex and connects the rear 25 ends of the side portions C².

The configuration of the inner edges of the portions of the body B just described above causes the recess C to appear. The face of the body B is roughened, and depressions D 30 appear in the rear portion C' near the rear ends of the portions C².

Having thus fully described my invention, I claim as new and desire to secure by Letters Patent—

The design for the horseshoe-pad, as herein shown and described.

In testimony whereof I have signed my name to this specification in the presence of two subscribing witnesses.

JACOB KRONENBERG.

Witnesses:

THEO. G. HOSTER,
EVERARD BOLTON MARSHALL.
